UNITED STATES PATENT OFFICE

ADOLPH G. SCHURMAN, OF BALTIMORE, MARYLAND

ANTIPIILFERAGE SEAL

Application filed October 2, 1929. Serial No. 396,737.

Manufacturers of various commodities are desirous of their product reaching the consumer without adulteration and therefore have designed many expedients to seal their containers, but it has been found that these seals may be broken, the commodity adulterated and again sealed and sold as the genuine article.

The object of my invention is to provide an anti-pilferage seal for containers that cannot be removed without destructive effort, and of such construction that it will be difficult and expensive to reproduce thereby giving a maximum security to the contents of the containers; and with this and other objects in view my invention consists of the parts and combination of parts hereinafter set forth.

In the drawing:

Figure 1 is a perspective view of my improved seal before its application to a container.

Figure 2 is a similar view of the seal as it would appear after its application to a container.

Figure 3 is a detail sectional view of a container with my seal applied.

The reference number 4 designates a container of any desired shape and size, having, preferably, but not necessarily, a spout 5, said spout terminating at its upper end in an inturned annular flange 6 which has an outer substantially horizontal portion and an inner conical or tapered portion, which latter extends at an inward and downward angle of inclination, as shown, and is of sufficient rigidity for the purposes of my invention.

My seal consists of a disc 7 which I prefer to have dished, as shown, is provided with a vertical flange 8 at the top of which is an outwardly extending annular flange 9 of less width than the flange 6 and of no greater width than the inner conical or tapered part of said flange 6. This disc or seal 7 is placed in the mouth of the spout with its flange 9 resting on the top edge thereof, the disc 7 and its flange 8 depending within the spout 5, as shown in Figure 3.

Now when the seal is in this position lugs

10 are upset by a suitable instrument from the flange 8 and projected underneath and in engagement with the underface of the flange 6 of the spout 5. The spout is then covered with the usual closure top 11.

As will be seen, the flange 6 is more or less rigid, and likewise, as a result of their formation the lugs 10 are rigid, therefore the flange 6 not only resists outward movement upon an attempt to remove the seal, but the seal cannot be removed or forced from the spout without a destructive effort; that is to say: In order to remove the seal it is absolutely necessary either to destroy the lugs 10, the flange 9 of the seal or the flange 6 of the spout whereby a consumer could readily see that the container has been tampered with and refuse to accept it.

The fact that the seal must be made by a special die because of its construction, and the fact that a special tool is necessary to form the lugs 10 after the disc is in the spout 5 ensures a maximum security against adulteration, thereby protecting the manufacturer as well as the consumer.

It will be observed that as the flange 9 is substantially coextensive in width with the downwardly and inwardly inclined inner part of flange 6, said flange 9 seats wholly in the depression formed by said downwardly inclined part of flange 6 and thus is arranged to lie flush with the outer horizontal part of said flange 6. By this arrangement the depressed part of flange 6 may be held closely between the flange 9 and the lugs 10 so that any attempt to release the seal 7 by either upward or downward movement will result in the flange 6 being bound the more firmly against the seal and resisting such movements thereof.

Also by this construction liability of injury to the seal flange 9 by contact with extraneous objects is prevented and it is not necessary to provide the rim of the receptacle neck with a guard or shield to lie around the flange 9 to protect the same from possible injury. Furthermore, the flush arrangement of the flange 9 provides the end of the container with a smooth and plane surface on which another cap may be stably

rested and which permits of a cap and sealing disk being fitted tightly and in a leak-proof manner against the same.

What I claim is:

5 / A container provided with a discharge spout having an inturned rigid marginal flange provided with a horizontal outer portion and an inner portion extending continuously at a downward and inward angle of inclination from said outer horizontal portion, and a seal for said spout having a closed bottom portion and an annular vertical flange projecting upwardly therefrom, said vertical flange having an outwardly extending horizontal flange at its upper edge lying wholly in the recess formed by

and overhanging the said downwardly and inwardly inclined portion of the marginal flange of the spout and resting upon said inclined portion of the flange so as to dispose its upper surface flush with the upper surface of the outer horizontal portion of said marginal flange of the spout, and annularly spaced outstruck lugs on the vertical flange of the seal extending under the downwardly and inwardly inclined portion of the marginal flange of the spout and holding the latter closely confined between said lugs and said horizontal flange of the seal. 70 75
